FREDRIK LJUNGSTRÖM, OF BREVIK, LIDINGÖN, SWEDEN, ASSIGNOR TO AKTIEBOLAGET LJUNGSTRÖMS ÅNGTURBIN, OF STOCKHOLM, SWEDEN.

CONDENSING APPARATUS.

1,330,081.

Specification of Letters Patent. Patented Feb. 10, 1920.

Application filed February 6, 1919. Serial No. 275,417.

To all whom it may concern:

Be it known that I, FREDRIK LJUNGSTRÖM, chief engineer, subject of the King of Sweden, residing at Brevik, Lidingön, Sweden, have invented certain new and useful Improvements in Condensing Apparatus for Locomotives, of which the following is a specification.

It is a known fact that the steam motor of locomotives is subjected to very great variations of load, the trains alternately running on uphill—or downhill—and on level lengths. Also in starting from or running into a station, and so forth, greatly varying loads are met with. Such variations of load, therefore, call for greatly varying requirements with regard to the ability of the condenser to condense the steam which is discharged from the steam motor and enters the condenser, the quantity of such steam changing from maximum to 0, often at intervals of only 1-2 minutes between the various full load periods. Therefore, the quantity of air required to effect the condensation of the steam is particularly variable, this circumstance having been one of the chief difficulties which has prevented the arrangement of a condenser in locomotives. These difficulties, in fact, have been so great that heretofore the arranging of condensers in locomotives has been wholly desisted from.

The present invention relates to a condenser arrangement for locomotives (or similar engines) which is intended for the use of an approximately constant quantity of air, thereby enabling a reduction of the dimensions of the air cooled condenser and of the total quantity of air forced through the air cooled condenser per unit of time, the air flowing through the air cooled condenser during the no-load periods being rendered active also for the full-load periods.

45 This will be obtained by building up the condenser partly of a condenser and partly of an accumulator in the form of a reservoir containing liquid and, if found suitable, one or more heat absorbing solid bodies. 50 This vacuum accumulator acts in such manner that it absorbs part of the steam through condensation during the full load periods, but, on the other hand, delivers a corresponding quantity of steam to the air cooled condenser during the no-load periods. In

this way the air cooled condenser, evidently, is rendered independent of the steam impulses to the condenser and the same no longer has to be constructed for maximum quantities of steam, its dimensioning for an average quantity of steam answering all requirements; the equalization takes place in the accumulator.

Various embodiments of the invention are shown in the accompanying drawings. 65

Figure 1 is a longitudinal section of a locomotive, tender or the like designed according to the invention.

Fig. 2 is a section on line 2—2 of Fig. 1.

Fig. 3 is a cross section on line 3—3 of Fig. 1.

Fig. 4 shows a detail of the condenser drawn to a larger scale.

Fig. 5 is a section on line 5—5 of Fig. 4.

Fig. 6 is a section on line 6—6 of Fig. 4. 75

Fig. 7 shows a detail of Fig. 1.

Fig. 8 shows in longitudinal section a modification of the arrangement represented in Fig. 1.

Fig. 9 is a sectional plan view of this 80 modification on the line 9—9 of Fig. 10, the upper part of Fig. 9 being a section on line 9—9 of Fig. 8, and the lower part a section on line 9'—9' of Fig. 8.

Fig. 10 is a front view of Fig. 8. 85

Fig. 11 is a cross section on line 11—11 of Fig. 8.

Fig. 12 is a longitudinal section of a further embodiment of the invention.

Fig. 13 shows the same in cross section on the line 13—13 of Fig. 12, and

Fig. 14 a further embodiment in cross section.

In the embodiment according to Figs. 1, 2 and 3, 1 denotes the air cooled condenser and 2 the accumulator containing a liquid, preferably water and, if desired, a solid heat absorbing material. The accumulator suitably has the form of an elongated cylinder. The water in the accumulator or water receptacle 2 absorbs part of the steam through condensation during the full load periods a corresponding quantity of steam being delivered by the said water to the air cooled condenser during the no-load periods. 100 105

The operation, briefly, is as follows:

Assuming that the air is passing the condenser in quantities sufficient to cool down the walls of the air cooled condenser 1 to 70°, and that the locomotive is running half 110

the time under full load and half the time without load, and that the variations in speed occur every minute; assuming further that the water has an initial temperature of 5 65° , then, in the full load period of the first minute half of the steam escapes into the air cooled condenser 1, which on account of the cooling action of the air retains its temperature of 70° , the other half of the 10 steam being condensed by the water contained in the accumulator 2, by which the temperature of the said water is raised to 70° . When the no-load periods set in obviously all delivery of steam from the steam 15 motor to the condenser ceases. On account of the cooling action of the air on the air cooled condenser the temperature of the latter falls rapidly so that a higher vacuum is produced in the same, corresponding to 20 the saturation temperature at a lower steam pressure. On account of this lower steam pressure the water in the receptacle of the condenser gives off steam to the condenser, the temperature of such water falling in 25 the meantime so that in the next full load period the said quantity of water will by the lower temperature thus obtained be ready once more to absorb through temperature rise half of the steam entering in the 30 full load period. Thus the water contained in receptacle of the condenser serves as a sort of vacuum accumulator by equalizing the load for the air cooler so that the latter in a case like the one above described has to 35 be only half as great as it would have to be without the accumulator.

To facilitate the steam absorption or delivery of the accumulator the same is provided with a circulating pump 3 and other 40 suitable means to bring the water into live contact with the steam by round-pumping and the forming of a series of water jets 4, cataracts or the like. This may be attained by placing a diaphragm 5 provided 45 with a series of apertures 6 above the water level, the said diaphragm being filled with water by means of the pump 3 so that the water forms a level with corresponding pressure on the diaphragm. Through the 50 apertures 6 of the diaphragm the water falls in a series of jets to the lower water level, thus facilitating a rapid and lively condensation or delivery of steam. The water jets are suitably formed into long and thin 55 water partitions by providing the diaphragm with apertures in the form of elongated narrow openings, thus giving the steam a good passage between the said water partitions in the longitudinal direction of 60 the vessel, without rendering the resistance offered to the steam flowing through the vacuum accumulator too great.

The air cooled condenser 1, which is disposed above the water accumulator, is provided with steam inlets at 7, outlets 8 for

the water of condensation and a connecting branch 9 for the air pump. The arrows shown in the drawing indicate the way taken by the steam through the condenser or vacuum accumulator during the full load 70 periods. It is to be observed that on account of the general construction of the condenser as a whole part of the steam passes directly into the air cooled condenser at 10. Assuming for instance that $\frac{1}{2}$ of the total 75 quantity of steam passes at 10, then $\frac{1}{2}$ of the total quantity flow partly over partly under the diaphragm 5 so that through the contact between steam and water one half of the total quantity of steam is condensed, 80 finally the remaining $\frac{1}{2}$ enters into the second half of the air cooled condenser 1 at 11.

By this arrangement the advantage is obtained that while the condensation is taking place in the air cooled condenser there 85 is always a flow of steam through the whole of the vacuum accumulator and through the passage 11 and condenser 1, whereby any air entrained with the steam enters with the steam into the air cooled condenser at 90 11, and is finally drawn off by means of the air pump at the branch connection 9. In this way the steam is subjected to a systematic thoroughly effected circulation through the condenser and the vacuum ac- 95 cumulator in such manner that all the air entrained with the steam is compelled to follow with it to the air pump connection, a circumstance making it possible to obtain an effective vacuum and to reduce the air 100 pump work to a minimum. The quantity of air to be pumped from the two different sections of the air cooled condenser may be suitably proportioned by the arrangement of suitable throttling holes 12 (Fig. 7) in 105 such manner, that in the present case for instance $\frac{1}{2}$ is taken from the one part of the air cooled condenser and $\frac{1}{2}$ from the second part of the said condenser, these quantities corresponding to the quantities of air which 110 in the course of the circulation get into the one or the other part of the air cooled condenser.

The air cooled condenser obviously may be constructed in a great many different 115 forms of which Figs. 4, 5 and 6 in the drawings show one embodiment. According to this form of construction the air cooled condenser is built up of a number of laminae 13, each formed of a plate corrugated at angles 120 of 45° relatively to the longitudinal direction, the said plate in the form of a flattened out pipe constituting the inside steam chamber of the laminae in which steam channels 18 are produced by the corrugations cross- 125 ing each other, the said channels communicating with each other at the crossings. A plurality of such laminae being disposed beside each other, similar channels 14 are produced between them the said channels cross- 130

ing each other and being also open toward each other at the crossing points. The cooling air is forced through the channels formed between the laminae, a particularly 5 favorable cooling effect being obtained thereby. This form of air cooled condenser is principally known through the Swedish Patents No. 7848 and No. 16724, and in the 10 present application only the special application of the air cooled condenser in combination with the vacuum accumulator and the connection of the cooling laminae with the steam chamber are claimed as novel characteristics.

15 The cooling laminae are connected with the steam space of the vacuum accumulator 2 by means of bent pipes 15. The pipes 15 are preferably soldered to the cooling laminae and connected with a common tube 20 plate 22 by means of screw-connections of known construction, or they may be attached to the plate in some other convenient manner. The said tube plate is 25 preferably constructed so as to secure air tight connections with the tubes 15. The air pump connection 9 is situated in the opposite end of the cooling laminae, and the water of condensation is drawn off directly 30 into the vacuum accumulator through a pipe 8 at any convenient point of the lower edge of the laminae. The air outlets of all cooling laminae are connected in two groups to a common air outlet 19 by means of collecting pipes 20 running transversely over all 35 laminae.

To obtain a sufficiently powerful air circulation through the air cooled condenser the air is sucked in at both sides preferably 40 through screen-like guide plates 16 directed obliquely forward, counting in the longitudinal direction of the locomotive, the relative speed between the locomotive and the surrounding air being thus utilized to effectively draw the air into the cooling apparatus. In the running periods, however, 45 the speed of the locomotive is varying greatly relatively to the surrounding air, and to overcome this drawback vertical propeller-fans 17 are disposed in conjunction with the guide plates 16 above mentioned, which fans are suitably driven from the steam motor or the wheel axles of the under-frame, the said fans forcing the air upward 50 through the condenser. The fans 17 are 55 suitably connected with thin driving means in such manner that the speed of the fans may be changed, when required, relatively to the speed of the locomotive.

The use of a high vacuum requiring considerable dimensions of the connecting passage between the steam motor 23 and the condenser, the steam motor 23 is preferably placed on the vacuum accumulator directly, or on the car carrying the same, and in 65 such case the energy of the steam motor is

transmitted to the wheel axles carrying the vacuum accumulator. This arrangement is shown diagrammatically in Fig. 1, the steam motor preferably being of the rotary type and transmitting its power to the wheel 70 axles by means of connecting rods.

In the embodiment shown in Figs. 8-11 an air drum 24 is arranged immediately above the accumulator 2, the said air drum being enlarged at 25 so as to provide sufficient 75 room for the fan 17. In this case the steam is conducted from the accumulator 2 up into the air cooled condenser 1 through the passage 26 situated by the side of the air drum 24. In this case the laminae of the air cooler 80 are placed in the transverse direction of the locomotive.

In the embodiment according to Figs. 12, 13 and 14 an air cooled condenser is provided on each side of a vertical plane, the 85 said condensers being arranged obliquely to this plane. The cooling air is taken in as described above with reference to Fig. 1, the air flowing through the condensers in the direction indicated by the arrows. In the 90 embodiment according to Fig. 14 the accumulator is of triangular cross section.

In most cases it will be found suitable to arrange the condenser and the accumulator on the same car in accordance with the 95 embodiments shown in the drawings, the steam motor also, if desired, being disposed on the said car. When the steam motor is not placed on this car, however the latter rather corresponds to the tender than to the locomotive in the arrangements employed at 100 present. The boiler, which may be provided with a superheater and an air-preheater, is arranged on another car corresponding to the locomotive when the steam motor is disposed on the same.

No matter how the boiler, superheater, steam motor, air cooled condenser and accumulator are arranged in relation to each other, the boiler and the condenser should be 110 disposed after each other, a number of various advantages being thereby obtained regarding the utilization of space, reduction of losses due to the cooling of the steam, increased supply of air to the air cooled condenser, and so forth.

Claims:

1. A condensing apparatus for locomotives including an air cooled condenser, a steam motor and a vacuum accumulator in 120 connection with the condenser and the motor and adapted at varying loads for alternately receiving steam from the motor and for discharging steam to the air cooled condenser.

2. A condensing apparatus for locomotives including in combination, an air cooled condenser, a steam motor, a vacuum accumulator adapted to contain water in connection with the condenser and the motor and adapted at varying loads for alternately re- 130

ceiving steam from the steam motor and discharging steam to the air cooled condenser and means in the accumulator for effecting a circulation of the water and subdividing some of the water into jets during the circulation.

3. An apparatus as claimed in claim 2 wherein the means includes, a diaphragm arranged in the accumulator and provided with a series of longitudinally disposed slots for producing jets, and a circulating pump between the diaphragm and the bottom of the accumulator.

4. A condensing apparatus for locomotives including in combination, an air cooled condenser, a steam motor, an inclosed cylindrical accumulator adapted to contain water in connection with the condenser and the motor adapted at varying loads for alternately receiving steam from the steam motor and for discharging steam to the air cooled condenser, a diaphragm arranged longitudinally of the accumulator and provided with a plurality of longitudinally disposed slots for producing water jets, a pump casting integral with and depending from the diaphragm and a rotary pump arranged in the pump casting for raising water from the bottom of the accumulator and causing it to flow over the diaphragm.

5. An apparatus as claimed in claim 1, wherein obliquely disposed screens are arranged on opposite sides of the condenser and in the direction of the movement of the locomotive for directing cooling air against the condenser.

6. An apparatus as claimed in claim 1, wherein a fan is provided to effect a sufficient draft of air against the air cooled condenser when the locomotive is running at low speed.

7. An apparatus as claimed in claim 1, wherein a fan is provided to effect a sufficient draft of air against the air cooled condenser and means between the fan and the locomotive for regulating the speed of the fan relative to the locomotive.

8. A condensing apparatus for locomotives including in combination, an air cooled

condenser composed of a plurality of corrugated laminae forming communicating steam passages, a steam motor, an accumulator arranged beneath the condenser and connected with the motor, inlet pipes arranged between one end of the laminae and the steam space of the accumulator, air pump connections associated with the opposite ends of the laminae, and outlet pipes between the laminae and the accumulator.

9. An apparatus as claimed in claim 8, wherein the condenser and the accumulator are elongated in the direction of movement of the locomotive whereby to permit cooling air to contact with the sides and bottom of the condenser.

10. An apparatus as claimed in claim 8, wherein the motor is connected directly to the accumulator to insure of the provision of steam passages of the desired length, the accumulator also being in the form of a cylinder, and heads in the accumulator to which the pipes are attached.

11. A condensing apparatus for locomotives, including an air cooled condenser, a steam motor and a vacuum accumulator in connection with the condenser and the motor and adapted at varying loads for alternately receiving steam from the motor and for discharging steam to the air cooler, the steam pipe from the motor exhausting into the accumulator.

12. A condensing apparatus for locomotives, including an air cooled condenser, a steam motor and a vacuum accumulator in connection with the condenser and the motor and adapted at varying loads for alternately receiving steam from the motor and for discharging steam to the air cooler, the steam pipe from the motor exhausting into the accumulator in such a way, that a part of the steam flows directly into the air cooler, another part, however, into the accumulator.

In testimony whereof I affix my signature in presence of two witnesses.
